[57] **CLAIM**

The ornamental design for a broom shroud, as shown and described.

DESCRIPTION

FIG. 1 is a front view of my new and ornamental design for a broom shroud, the rear view being a mirror image thereof;

FIG. 2 is a top view thereof;

FIG. 3 is a left side view thereof;

FIG. 4 is a right side view thereof; and,

FIG. 5 is a front perspective view thereof.

The broken lines are for illustrative purposes only and form no part of the claimed design.
